(57) **CLAIM**

The ornamental design for a television support tilt mechanism, as shown and described.

DESCRIPTION

FIG. 1 is a top, front perspective view of a television support tilt mechanism showing our new design;

FIG. 2 is a top, rear perspective view thereof;

FIG. 3 is front side elevational view thereof;

FIG. 4 is a rear side elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a top, front perspective view thereof, showing the television support tilt mechanism in operation.

The broken lines depict portions of the television support tilt mechanism that form no part of the claimed design.
